DISPENSER FOR SHEET PRODUCTS IN ROLL FORM

Harold J. Vanderhyde, North Merrick, N.Y., assignor to
The Procter & Gamble Company, Cincinnati, Ohio, a
corporation of Ohio

Filed Mar. 29, 1965, Ser. No. 84,475

Term of patent 14 years

(Cl. D52—2)

Fig. 1

Fig. 5

Fig. 3

Fig. 2

Fig. 4

Fig. 6

FIG. 1 is a front elevational view of a dispenser for sheet products in roll form showing my new design.

FIG. 2 is an end elevational view thereof.

FIG. 3 is a plan view thereof.

FIG. 4 is a cross sectional view thereof on the line 4-4 of FIG. 3.

FIG. 5 is a view similar to FIG. 1 but showing another embodiment of the design; and

FIG. 6 is a perspective view thereof.

I claim:

The ornamental design for a dispenser for sheet products in roll form, as shown and described.
